GEORGE STEWARD MACLEOD, OF SEATTLE, WASHINGTON, ASSIGNOR OF ONE-HALF
TO ANGUS P. MACLEOD, OF SEATTLE, WASHINGTON.

BUMPER FOR MOTOR-VEHICLES.

1,365,522.

Specification of Letters Patent. Patented Jan. 11, 1921.

Application filed May 25, 1920. Serial No. 384,038.

To all whom it may concern:

Be it known that I, GEORGE S. MACLEOD, a citizen of the United States, residing at Seattle, in the county of King and State of Washington, have invented a new and useful Bumper for Motor-Vehicles, of which the following is a specification.

This invention relates to buffers or bumpers designed to be attached to the front and rear of motor vehicles.

The principal objects of the invention are to provide a buffer of few parts, which is easy to manufacture and assemble, which is rattle-proof and which is highly resilient.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:—

Figure 1 is a top plan view with parts shown in section of the improved bumper.

Fig. 2 is a front elevation of the same.

Fig. 3 is a section on the line 3—3 of Fig. 1.

Fig. 4 is a section on the line 4—4 of Fig. 1.

Fig. 5 is a section on the line 5—5 of Fig. 1.

In the drawing, the numeral 6 denotes the main spring of the bumper, which spring is made up of a single piece of spring steel bent to form a loop with its ends brought together and abutted as indicated at 8. For the main portion of its length, the loop formed by the main spring comprises two parallel portions, and the loop at its ends is bent as indicated at 7, so that the bumper will curve around in front of or to the rear of the wheels of the vehicle, as the case may be. The opposite sides of the loop are equidistant throughout the entire length of the loop.

The main spring is held upon the car by brackets 9 which may be of any type, and, not entering into the present invention, will not be further described. These brackets support the main spring on that side of the

loop which has the joint 8, so that the unbroken or continuous side of the loop is presented outwardly with respect to the car.

The main spring incloses a supplemental spring 10 which is nothing more than a single leaf of spring metal secured intermediate its ends to the main spring. Such a supplemental spring will preferably be thicker at its middle than at its ends and will have a pair of wings 11 provided at each end for snugly fitting over the edges of the main spring. The supplemental spring bridges the joint between the ends, as indicated in Fig. 1, and is secured to each end by a pair of bolts 12. The bolts 12 pass through alined perforations provided in each side of the loop midway between the ends of the loop. Sleeves 13 are held upon the bolts 12 and act as spacers to hold the sides of the loop apart at their central portion where the supplemental spring is secured thereto. Obviously the bolts and spacing sleeves prevent any relative movement whatever of the sides of the loop at the central portion of the loop.

Throughout the remainder of the loop, on either side of the spaced-apart section, the main spring is free to contract or expand under blows or the like. The ends of the supplemental spring 10 are pressed by the resilience of that spring against the inner face of the outer side of the main spring, and when the main spring contracts or is otherwise deformed, the ends of the supplemental spring may slide freely along the main spring. The length of the supplemental spring is such that its ends press against the outer side of the loop at points nearly opposite where the main spring is supported by the brackets 9. The wheels of the vehicle will be normally directly back of the bent ends 7 of the loop, or if the bumper is used on the rear end of the vehicle the rear wheels will be in front of said bent ends.

One of the features of the invention is believed to be the provision of the spacing elements 12, 13 which hold apart the sides of the loop and secure the supplemental spring in place, and, which, in coöperation with the supplemental spring, hold the ends of the main spring together.

Another feature is believed to be the provision of a supplemental spring of the character described, which obviously adds

greatly to the resilience and strength of the bumper but does not permit any rattling of the parts, and which, being slidably engaged at its ends with the main spring, 5 yields freely without danger of breakage when the bumper encounters an obstruction.

The invention represents a construction which is extremely simple and economical 10 to manufacture and assemble, which is easily installed on a car, has a pleasing appearance, and meets all the requirements of the trade.

What is claimed is:

15 1. In a bumper for motor vehicles, a main spring forming a complete loop, a supplemental spring within the loop, and means joining the supplemental spring at a midpoint to one side of the main spring with the 20 ends of the supplemental spring engaging the other side of the main spring.

2. In a bumper for motor vehicles, a main spring forming a complete loop, a supplemental spring within the loop, and means 25 joining the supplemental spring at a midpoint to one side of the main spring with the ends of the supplemental spring engaging the other side of the main spring, said means also holding the two sides of the 30 looped spring apart at a midpoint of the loop.

3. In a bumper for motor vehicles, a main spring forming an elongated loop with parallel sides, the ends of the spring being 35 brought together at a midpoint of the loop, means for bridging the two ends, and means holding the bridging means spaced from the opposite side of the loop.

4. In a bumper for motor vehicles, a main 40 spring forming an elongated loop with parallel sides, the ends of the spring being brought together at a midpoint of the loop, means for bridging the two ends and for resiliently supporting the opposite side of 45 the loop, and means holding the bridging means spaced from the opposite side of the loop.

5. In a bumper for motor vehicles, a main 50 spring formed into an elongated loop with the ends brought together at a point midway between the ends of the loop, a supplemental spring within the loop and secured to the main spring at each end and bridging said ends, said supplemental spring having

its ends engaging the opposite side of the 55 loop at points removed from the middle thereof.

6. In a bumper for motor vehicles, a main spring formed into an elongated loop with the ends brought together at a point midway between the ends of the loop, a supplemental spring within the loop and secured to the main spring at each end and bridging said ends, said supplemental spring having its ends engaging the opposite side 60 of the loop at points removed from the middle thereof, and wings on each end of the supplemental spring for holding those ends to the main spring when the latter expands or contracts.

7. In a bumper for motor vehicles, a main spring formed into an elongated loop with the ends brought together at a point midway between the ends of the loop, a supplemental spring formed of a single leaf, 75 securing means holding the supplemental spring to the main spring at points near the ends of the latter, said supplemental spring having its ends engaging with the opposite side of the loop, said securing means spacing the two sides of the loop apart at the middle portion of said loop.

8. In a bumper for motor vehicles, a main spring formed into a loop, a pair of brackets securing the loop to the car, and a supplemental spring secured within the loop to that side carried by the brackets, the free ends of said supplemental spring bearing against the opposite side of the loop at points approximately opposite where the 80 brackets hold the loop.

9. In a bumper for motor vehicles, a main spring formed into an elongated loop, a supplemental spring within the loop, spacing elements located at a point midway between the ends of the loop and arranged within the same and secured to the main spring, said spacing elements serving to hold the supplemental spring in place, said supplemental spring having its ends engaging the side of the loop opposite that side 95 where secured to the loop, said ends engaging the loop at points removed from the middle thereof.

In testimony, that I claim the foregoing 100 as my own I have hereto affixed my signature.

GEORGE STEWARD MACLEOD.
